C. H. Knowlton,

Operating Jacks in Looms.

No 96,925.

Patented Nov. 16. 1869.

Fig. 1.

United States Patent Office.

CHARLES H. KNOWLTON, OF CAMDEN, NEW JERSEY.

Letters Patent No. 96,925, dated November 16, 1869.

IMPROVEMENT IN MECHANISM FOR OPERATING THE JACKS IN LOOMS.

The Schedule referred to in these Letters Patent and making part of the same.

To all whom it may concern:

Be it known that I, CHARLES H. KNOWLTON, of Camden, New Jersey, have invented a Device for Operating the Jacks of Looms; and I do hereby declare the following to be a full, clear, and exact description of the same.

My invention consists of certain arms, hinged to and reciprocating with a jack-frame, and so controlled by levers, or their equivalents, that they shall be the means, through the jacks, of causing the heddles to open the warp-threads to a greater extent, as the said heddles recede from the shuttle, thereby preventing that undue strain to which the said threads are subjected when opened by the usual jack, all of which is fully explained hereafter.

In order to enable others skilled in the art to make and use my invention, I will now proceed to describe its construction and operation, reference being had to the accompanying drawing, which forms a part of this specification, and in which—

Figure 1 shows the side-frame of a loom, with my improved mechanism for operating the jacks;

Figure 2, a view of fig. 1, looking in the direction of the arrow; and

Figure 3, a diagram, illustrating the purport of my invention.

A represents the side-frame of a loom, and B, part of the crank-shaft, on the end of which, outside the frame, are two cranks *a* and *a'*, fig. 2, the crank *a* being connected by a link, *b*, to a rod, B, which is arranged to slide in guides on the frame A of the loom, and the crank *a'* being connected to a similar sliding rod, D', by a link, *b'*.

The cranks are so arranged that on rotating the shaft B, a reciprocating motion, in contrary directions, will be imparted to the two sliding rods, one rod ascending while the other is descending.

The upper end of the rod D' is connected, by a cross-bar, E, to a suspension-rod, F, and the other sliding rod, by a similar cross-bar, to a similar suspension-rod, F'.

To the lower end of the rod F is jointed a rod, G, and to the rod F' is jointed a similar arm, G', both arms passing through and being guided by slots in a projection, *i*, attached to the frame of the loom.

On the outer end of the arm G is a pin, *d*, which passes through a slot in a projection, *e*, on the sliding rod D', a similar pin on the arm G' passing through a slot in a similar projection on the sliding rod D'.

The pin *d* of the arm G is embraced by the forked short arm of the lever H, hung to the sliding rod D', adjacent to the slot in the projection *e*, the long

arm of the lever passing through an eye in a stationary bar, J.

In like manner, a pin on the end of the arm G' is embraced by the forked short arm of a lever, H', hung to the rod D, the long arm in this lever passing through an eye in a stationary bar, J.

In ordinary fancy-looms the well-known jacks, connected to the harness, are operated by two reciprocating frames, in some respects similar to those described.

The important difference between the old reciprocating frames and my improved device for operating the jacks is this, that the bars (in the old frames) which come in contact with the projections of the jacks are permanent, whereas the bars, or, as I have termed them, the arms G and G', in my improved device have a peculiar movement imparted to them.

For instance, as the rod D' reciprocates, it will carry with it the rod F and the arm G, but the position of the outer end of the arm is so controlled by the lever H that the arm must vibrate on the end of the rod F, and the same remarks will apply to the arm G, and this vibration is so regulated by the arrangement of the moving parts that when the arm G is at its most elevated position, and the arm G' at its lowest position, the two arms will be inclined, as shown in fig. 1, and this is the condition when the warp-threads are open, for the passage between them of the shuttle.

It will scarcely be necessary to describe the action of these arms on the jacks, but I have shown in red lines, fig. 2, one of a row of jacks, to be operated by a pattern chain in the usual manner, so as to be brought under the control of the arm G, or under that of the arm G', as the chain may be determined, with a result too well known to those skilled in the art to need description.

The advantage of my invention will be best understood by reference to the diagram, fig. 3, where *k* represents part of a woven fabric, *m m*, the open warp-threads, *n n*, a number of heddles, connected to as many jacks, and *p*, the shuttle, in the act of passing between the open warp-threads.

When an ordinary reciprocating jack-frame is used, the warp-threads will be spread in the manner indicated by the red lines *t t*; that is to say, all the warp-threads will be opened to the same extent; hence, the threads which are acted on by the heddles nearest the shuttle are subjected to a severe strain, to avoid which is the special object of my invention.

The inclination given to the arms G and G', in the manner described above, is such that when they have acted on the jacks to open the warp-threads, the extent of the opening of the latter will vary.

For instance, those nearest the shuttle will be opened to a less extent than those further from the shuttle; or, in other words, the opening of the warp-threads will be gradual from the rearmost heddle x to the point y , where the weft-thread has been beaten up into the fabric; hence the above-mentioned undue strains, to which the warp-threads are subjected by the operation of ordinary jack-frames, is obviated.

I claim as my invention, and desire to secure by Letters Patent—

A rigid reciprocating frame, sliding on a loom, and having one or more arms G , vibrated substantially as and for the purpose described.

In testimony whereof, I have signed my name to this specification, in the presence of two subscribing witnesses.

CHAS. H. KNOWLTON.
